UNITED STATES PATENT OFFICE

MAX GENSER, OF PROVIDENCE, RHODE ISLAND, ASSIGNEE TO GENSER MANUFACTURING COMPANY, INC., OF PROVIDENCE, RHODE ISLAND, A CORPORATION OF RHODE ISLAND

MEANS FOR ATTACHING PIN-TONGUE MOUNTINGS TO JEWELRY

Application filed January 23, 1929. Serial No. 334,515.

This invention relates to an improved pin-tongue mounting for use on brooches, bar pins and other similar articles of jewelry, particularly with jewelry having a setting for precious stones, pearls, gems or brilliants.

One object of the invention is to provide a pin-tongue mounting having its parts so arranged as to be practically entirely concealed from view in the normal position of the article.

Another object of the invention is to provide a pin-tongue mounting which may be secured to the article of jewelry without soldering.

Another object of the invention is to provide a pin-tongue mounting which may be secured to the article by the gem-setting itself without the use of other fastening means such as pins, rivets or the like.

Another object of the invention is to provide a mounting of the type specified which may be used either for the pin-tongue or its catch, and which will be stronger and more durable in use than present mountings for the same purpose.

Further objects of the improvement are set forth in the following specification which describes a preferred embodiment of the invention as illustrated in the accompanying drawings. In the drawings:

Fig. 1 is a front view of a conventional design of brooch illustrating one form of construction of the invention;

Fig. 2 is a rear view of the brooch illustrated in Fig. 1;

Fig. 3 is an enlarged plan view of a portion of the brooch showing the gems removed from certain of the settings to illustrate the arrangement of the parts;

Fig. 4 is a side view of the structure illustrated in Fig. 3, showing the arrangement of the improved pin-tongue mounting in connection therewith;

Fig. 5 is a detailed sectional view on line 5-5 of Fig. 3, showing the relation of the pin-tongue mounting to one of the gem-settings;

Fig. 6 is a perspective view of the gem-setting; and

Fig. 7 is a perspective view of the pin catch.

In the construction of certain articles of jewelry it is highly desirable that all of the mechanical parts be concealed from view, so far as possible, in order that the brilliancy of the gems may be undiminished and that the gems may, in fact, present the appearance of being unsupported by any metallic parts.

In the embodiment of my invention as herein illustrated 1 designates an annular metal plate constituting the frame of a brooch which is provided with a plurality of adjacent openings 2 for the reception of the reduced tubular necks 3 of gem-settings 4. The gem-settings 4 are of concavo-convex shape in the present instance to adapt them to receive pearls or gems 5 of substantially spherical shape, the edges of each setting being provided with prongs 6 adapted to be bent over upon the outer surface of the gem to retain it in place.

As herein shown an elongated bar 8 is employed to connect opposite sides of the annular frame 1 whereby to reinforce its structure. In the present instance the bar 8 is illustrated as formed integral with the annular frame 1, although the particular construction and arrangement of the bar and the manner of its connection forms no part of my present invention.

A plurality of the gem-settings 4 are secured to the annular frame 1 by inserting their reduced necks 3 in the openings 2 spaced around the frame. The end portion of the reduced neck 3 of each gem-setting which projects beyond the frame 1 is then swaged or riveted over as indicated at 9 to firmly secure the setting to the frame. The gems 5 may then be placed in the settings and secured thereto by bending over the prongs 6 in the manner as usually employed in the present art.

In accordance with the present invention, two oppositely positioned gem-settings 7 are provided with reduced tubular neck portions 3 of somewhat greater length than the other settings in order that their ends may extend through an additional thickness of metal to

serve as the attaching means for the pin-tongue mounting and the catch for the pin.

- These two gem-settings 7 may be located upon opposite sides of the annular frame 1, as shown in Figs. 1 and 2, the increased length of the reduced necks 3 thereof being such as to permit them to pass through a portion of the pin-tongue hinge-member and catch respectively.
- 10 The pin-tongue 10 as usually constructed is provided at one end with a loop 11 for pivotal connection with projections or studs 12 on the hinge-member 16. The hinge-member 16 is formed from sheet-metal with opposite spaced sides 15 bent around to engage the studs 12 with the loop 11. The hinge-member 16 is provided with an annular base or ring 17, the central opening 18 of which is adapted for the reception of the
- 15 reduced neck 3 of one of the two oppositely positioned gem-settings 7. In assembling the parts, the reduced neck 3 of one gem-setting 7 is passed through the proper opening 2 in the frame 1 and inserted through the
- 20 opening 18 in the annulus 17. This may be accomplished before the hinge-member 16 is bent into shape to engage the studs 12 with the loop 11 on the pin-tongue 10 whereby to give access to the projecting end of the reduced neck 3 so that it may be more readily swaged over to connect the hinge-member with the frame 1 as shown in Fig. 5.

The pin catch 20 may also be provided with a flat annular portion 21 having a central opening 22 and a curved beak or hook 23 for engaging the end of the pin-tongue. The pin catch 20 is secured to the annular frame 1 by passing the reduced neck 3 of the oppositely positioned gem-setting 7 through the opening 22 and swaging its end thereover in the manner as explained in connection with the hinge-member 16. The flat portion 21 of the pin catch is thus firmly secured to the back of the frame 1 in such position that the curved beak 23 will be suitably related to engage or hook over the free end of the pin-tongue 10 in pinning the brooch to the apparel.

It will be observed from the foregoing that my improved structure provides for mounting the pin-tongue hinge-member and the pin catch in such manner that their supports are entirely concealed from view by the gems held in the settings, which latter elements serve as a means for securing the parts together. This improved construction renders it possible to provide a pin-tongue mounting for various articles of jewelry with its supports entirely concealed from view and thus not detracting from the appearance of the gems or other ornaments in the setting. The invention also provides a rigid, secure means for connecting the pin-tongue supports to the frame of the article without the necessity of soldering the parts

and without the use of pins, screws or the like.

Moreover, by securing the pin-tongue supports to the article by means of the gem-settings a more compact structure is provided than is possible with the use of separate fastening devices; the elimination of rivets, screws or extraneous securing means resulting in the concealment of the entire mechanical structure.

While I have herein shown and described a single embodiment of the invention, it is to be understood that various modifications in the form and arrangement of the parts of the device may be made without departing from the spirit and scope of the invention as set forth in the appended claims.

Therefore, without limiting myself in this respect, I claim:

1. In an article of jewelry, a frame having an opening, a pin-tongue support having a base seated against the back of the frame and provided with an opening registering with the opening therein, and a gem-setting provided with a reduced neck portion inserted through the opening in the frame and the opening in the pin-tongue support and riveted over on the base of the latter to secure the parts permanently in place.

2. In an article of jewelry, a frame having a plurality of openings, a pin-tongue support seated against the back of the frame and provided with an opening registering with one of the openings therein, and a gem-setting constructed with a portion seated against the front of the frame and provided with means for holding a gem, said gem-setting being formed with a tubular neck portion inserted through one of the openings in the frame and through the opening in the pin-tongue support with its end swaged over against the latter to permanently secure the parts together.

3. In an article of jewelry, a body member having a hole therethrough, a pin stem mounting member formed of sheet stock having a stem receiving head portion and a pierced flat base portion connected to the head by a foldable neck portion, a gem setting member having a tubular shank extending thru the hole in the body and piercing in the base and riveted over the latter to secure both to said body member on opposite sides thereof by a single riveting operation, the neck portion of the mounting member being subsequently folded to position the head portion over the riveted base portion.

4. In an article of jewelry, a pin joint having a flat base portion with an opening and pin joint parts bent therefrom, a pin catch having a flat base portion with an opening, a body member having flat portions with openings aligned with said pin joint and pin catch openings, tubular gem settings passing through said aligned openings and lock-

ing said pin joint and said pin catch to said body member and a pin pivotally mounted in said pin joint and engageable with said pin catch.

5 5. A pin mounting member comprising a base, a head positioned perpendicular to said base, two parallel ears projecting from the sides of said head and having indentures in aligned adjacency, and a bar projecting from 10 the end of one ear towards the other ear.

In testimony whereof I affix my signature.
MAX GENSER.
